[57] CLAIM

The ornamental design for an interior cargo cover for motor vehicles, as shown and described.

DESCRIPTION

FIG. 1 is a perspective view of an interior cargo cover for motor vehicles showing my new design;

FIG. 2 is a top plan view thereof;

FIG. 3 is a bottom plan view thereof;

FIG. 4 is a left side elevational view thereof;

FIG. 5 is a right elevational view thereof;

FIG. 6 is a front elevational view thereof; and,

FIG. 7 is a back elevational view thereof.

The broken line showing of environment is for illustrative purposes only and forms no part of the claimed design. The broken lines shown along the border and along the seam of the interior cargo cover are understood to represent stitching.
